UNITED STATES PATENT OFFICE.

HENRY L. PECK, OF COLUMBUS, OHIO.

BURGLAR-ALARM.

SPECIFICATION forming part of Letters Patent No. 364,540, dated June 7, 1887.

Application filed August 18, 1886. Serial No. 211,191. (No model.)

To all whom it may concern:

Be it known that I, HENRY L. PECK, a citizen of the United States, residing at Columbus, in the county of Franklin and State of Ohio, have invented certain new and useful Improvements in Burglar-Alarms; and I do hereby declare the following to be a full, clear, and exact description of the invention, such as will enable others skilled in the art to which it applies to make and use the same.

My invention relates to burglar-alarms, and contemplates certain new and useful improvements therein.

The object of my invention is to provide a burglar-alarm simple in its parts, reliable in its action, and in every way convenient, by means of which any one in the apartment where my box is located can at a glance ascertain whether a door or window of the building itself or any outhouse belonging thereto is being tampered with, and if so, can immediately determine the exact location of said door or window.

A full, clear, and exact description of my invention will be found in the following specification, reference being had to the accompanying drawings, in which—

Figure 1 is a view, in perspective, of the alarm-box. Fig. 2 is a vertical cross-section on line $x-x$ of Fig. 1. Fig. 3 is a vertical longitudinal section on line $y-y$ of Fig. 2. Fig. 4 is a diagram showing the manner of connecting my alarm-box to doors and windows. Fig. 5 is a perspective view of the appliance for connecting an outwardly-opening door to my alarm-box. Fig. 6 shows a connecting device for windows. Fig. 7 represents an appliance for connecting to inwardly-opening doors. Fig. 8 represents a group of bell-crank levers, located when in use directly over the alarm-box. Fig. 9 is a detail view, in perspective, showing the mode of attaching the connecting-wire to the alarm-box. Fig. 10 represents one of the indicator-slides. Fig. 11 shows my device for line attachment to an outwardly-opening door.

My alarm-box A may be of any convenient size, and is provided with two swinging shutters, B and B', upon the inner sides of which are inclined projections b. Inside the box A,

located near the lower edge of each shutter, are the frames $a-a'$. These frames are mounted in bearings in which they turn, and are made heavier in their rear portion. They are connected in such manner that if one frame is moved the other moves with it, the two being always parallel, and when the shutters are closed, horizontal.

Near the top and center of the box just in the rear of the partitions H H', mounted in 60 bearings, which allow them to turn, are the rods c c' c' c''. Loosely mounted on these rods are the spring-tongues d' d'' d' d'' d' d'' d'' d'' d''. Mounted rigidly on these rods are the tongues d d'' d'' d''. The tongues d' d'' d' d'' are provided with arms e, rigidly attached thereto. There are also mounted upon these rods and rigidly attached thereto the arms e', which operate the rigidly-mounted tongues.

In the top of the box A is an opening, G, 70 sufficiently long to permit wires attached to each of the arms e e' to extend vertically upward therethrough. This opening may be provided with cross-bars for the purpose of keeping the wires attached to the different 75 tongues and arms separate. Directly over this opening is fixed the group of bell-crank levers D. (Shown in detail in Fig. 8.) These are equal in number to the spring-tongues and are connected thereto by a series of wires 80 attached to said levers at the points g, and are connected at the points h with other wires attached to the windows and doors throughout the building. The ends of each of the above-mentioned tongues protrude outward through 85 openings in the partitions H H', and upon these ends are suspended the indicator-slides F, Fig. 10, the inner sides of which are inclined near their upper extremities, and such slides are provided below said inclined portion with shoulders f, by means of which they may be suspended on the spring-tongues.

The outer side of the indicator-slides are provided with recesses, in which the names of the different apartments may be inserted, and a finger-recess may be made near their lower extremities to facilitate the operation of raising the indicator when necessary. The slides are suspended upon the tongues, between the partition H H' and the front side of the box, 90 95 100

in such a manner that should any one of them drop it would come in contact with the forward portion of one of the frames a , and, being of sufficient weight to overbalance the 5 heavier rearward portion of said frames, would tip the same forward. Rigidly attached to the frame a is the arm a^2 , which engages a moving portion of an alarm-clock-work mechanism, which is located in the interior of the box.

10 In one end of my alarm-box is the door K , mounted on spring-hinges and provided with a keeper, k . This keeper is placed at such a height that when the door is closed and the frame a is permitted to take its normal position the said keeper will be engaged by a rearwardly-extending portion of said frame. At the points h of the bell-crank levers and diverging therefrom are wires attached to the different windows and doors through the 15 building. These wires may be attached to the windows and doors in any desired manner; but the following is a description of the appliances which I prefer to employ for that purpose:

20 For connecting a window with my alarm-box I use the device shown in Fig. 6, consisting of the plate M , rigidly attached to the top of the lower window-frame. This plate is provided with ears, between which is pivoted the 25 arm M^2 , extending slightly beyond the pivot toward the frame, and being so constructed that the point m of the said arm can be raised no higher when the window is closed, as shown in Fig. 6. Pivoted to the arm M^2 , and about 30 midway of the same, is an arm, M^3 , which engages the upper window-frame. This arm may be of the preferred shape shown in Fig. 6, or of any other desired form. The upper window-frame is provided with a recess, M^4 , 35 in which the rounded portion of the arm M^3 may be inserted. A wire is connected to the arm M^2 at the point m , the other end of which, by means, perhaps, of a number of bell-crank levers, is finally attached to one of the levers 40 in the group D , which is in turn connected with one of the wires extending therefrom to the alarm-box. When the lower window is raised, it is apparent that the end of the arm M^2 , to which the wire is joined, will be lowered. 45 This at once causes the bell-crank levers to turn, which pulls up the wire attached to one of the spring-tongues—for instance, d^4 . This retracts the tongue until it releases the indicator suspended thereon, which falls upon the 50 forward portion of the frame a , striking in its descent the incline b on the shutter B , causing the latter to open, thus disclosing the name of the apartment. The weight on the frame causes said frame to tip forward, thereby raising 55 the arm a^2 , which releases the clock mechanism and causes an alarm, and also freeing the spring-door K , which opens and allows the sound of the gong to escape.

60 The device which I use to connect my alarm-box with an inwardly-opening door is different from that used with an outwardly-opening door. The former consists of a bracket, N ,

rigidly secured to the wood-work just above the door. Pivoted to this bracket at the point n is the arm N' , Fig. 7. To the free end of this arm or lever is attached a wire connected, in the manner heretofore described, with one of the spring-tongues of the alarm-box. This arm is prevented from rising above its operative position by the stop n' . On the pivot n 70 is also mounted the angular plate-piece N^4 , the pivot passing through a curved slot, r , in said plate. The horizontal portion N^5 of this plate extends inwardly to near the end of the bracket N , and is provided near its extremity with a pin, n^2 , which engages a notch or recess in the bracket. This angular plate-piece is provided 75 near the junction of its members with a small lip, n^3 , projecting over the arm or lever N' a short distance from its pivot, and the arm or lever N' is provided with a lip projecting under the rearwardly-extending arm N^6 of the angular plate-piece. The pendent arm of this plate-piece when in its lowest position is in the path of the door when moved inward, and 80 the door coming in contact therewith will cause the same to move, by reason of its engagement with lever N' through lips n^3 and n^4 , and move said lever, causing an alarm, as heretofore described. The inner side of the pendent arm N' is made inclined, so that on closing 85 the door will raise the same out of its path, the arm moving freely upward on the pivot n by reason of the slot r .

I may, instead of operating the angular plate directly by the door, employ the plate mounted adjustably upon the inner side of the door. This plate is shown in the drawings as mounted in guide-loops o , attached to the door and provided with the inwardly-extending 90 arm P , having an upward projection, p ; but this plate may be attached to the door in any other desired manner. For example, the said plate may be provided with one or more slots and be attached to the door by screws passing 95 through the same. This plate is made adjustable, so that when moved downward into its lowest position it will pass beneath the pendent arm of the angular plate-piece, and while thus depressed the door can be freely opened 100 and closed without setting the alarm mechanism into operation; but when raised to its higher position, on opening the door it will engage the pendent arm of the plate-piece, and 105 an alarm will be sounded.

110 My device used to connect the alarm-box with outwardly-opening doors consists of a bent frame, R , attached firmly to the under side of the upper cross-piece of the door-frame, and yoke R' , sliding on said frame R by means 115 of the loops s .

120 To the frame part of the yoke is attached a connecting-wire. Secured to the door by means either of guide-loops or screws passing through the slots s' is the adjustable catch R^2 , 125 designed to engage the yoke at the point T when the catch R^2 engages the yoke R' , which, being connected with the box A , causes an alarm in manner hereinbefore set forth. As

130

- the door continues to open the yoke slides along the frame R until the portion of said frame which is bent upward raises the yoke until the catch R² is released, and thus prevents 5 breakage.
- What I desire to claim, and secure by Letters Patent, is—
1. In a burglar-alarm, a series of detached gravity-indicators, a series of spring-tongues 10 for supporting said indicators, and connections from said tongues to doors and windows of a building, substantially as described.
  2. In a burglar-alarm, an alarm mechanism, a pivoted weighted frame provided with an 15 arm normally engaging said alarm mechanism and serving as a detent for the same, a weight and spring-tongue engaging and supporting the same above said weighted frame, and connections leading from said spring-tongue to 20 the door or window, substantially as described.
  3. In a burglar-alarm, a box inclosing the operative parts, provided with a hinged shutter, B, having the incline b, in combination with gravity-indicators and spring-tongues 25 supporting the same above said hinged shutters, and line-connections, substantially as described.
  4. In a burglar-alarm, the combination, with a box inclosing the operative parts thereof, 30 having a spring-door provided with a stationary keeper, of a movable frame engaging said keeper, serving as a detent to the alarm mechanism, and devices for actuating said movable frame, substantially as described.
  5. In a burglar-alarm, the combination, with the alarm mechanism, of two pivoted weighted frames connected together, one of said frames serving as a detent for said mechanism, weights 35 and spring-tongues for supporting the same above each of said frames, and line-connections, substantially as described.
  6. The combination, with the spring-tongues, of the weighted indicators provided with the inclined top portion and supporting-shoulders, 40 substantially as described.
  7. The combination, with the spring-tongues, of the gravity-enunciators provided with an inclined top portion, the supporting-shoulders, and the finger-recesses, substantially as 45 described.
  8. In a burglar-alarm, the combination, with a pivoted frame serving as a detent for the alarm mechanism, of a series of weights and spring-tongues supporting them above said frame and line-connections, substantially as 50 described.
  9. The combination, with a stationary part and a movable part of a building, of a bracket, an alarm connected with said movable device rigidly secured to one of said parts, a movable 55 device mounted upon said bracket, and an arm attached to the other part of the building and engaging the movable device, substantially as described.
  10. The combination, with the bracket N, 60 and the lever pivoted thereon, of the slotted elbow-plate mounted on the pivot of said lever and engaging said lever, and an alarm connected with said lever, substantially as described.
  11. The combination, with the bracket N, 65 of the slotted elbow-plate pivoted with lip n³ and mounted on the pivot of said lever, an alarm, and a line connecting the lever and the alarm, substantially as described.
  12. The combination, with a door in its frame, of the bracket N, attached to the frame, the lever pivoted thereon, and a line-connection attached thereto, the slotted elbow-plate 70 mounted on the pivot of the lever, and the adjustable slide o, attached to the door, substantially as described.
- In testimony whereof I affix my signature in presence of two witnesses.

HENRY L. PECK.
